FISHING LURE

William D. Storm, Norman, Okla., assignor to
Storm Plastics, Inc., Norman, Okla.

Filed July 16, 1975, Ser. No. 596,107

Term of patent 14 years

Int. Cl. D22—05

U.S. Cl. D22—28

FIG. 1

FIG. 2

FIG. 3

FIG. 4

FIG. 5

FIG. 1 is a side elevation view showing one embodiment of my new design in a fishing lure.

FIG. 2 is a plan view of the fishing lure shown in FIG. 1.

FIG. 3 is a front elevation view of the embodiment of the fishing lure shown in FIG. 1.

FIG. 4 is a rear elevation view of the fishing lure embodiment shown in FIG. 1.

FIG. 5 is a bottom plan view of the fishing lure shown in FIG. 1.

FIG. 6 is a side elevation view showing a second embodiment of my fishing lure design.

FIG. 7 is a top plan view of the fishing lure shown in FIG. 6.

FIG. 8 is a front elevation view of the fishing lure shown in FIG. 6.

FIG. 9 is a rear elevation view of the fishing lure shown in FIG. 6.

FIG. 10 is a bottom plan view of the fishing lure shown in FIG. 6.

I claim:

The ornamental design for a fishing lure, substantially as shown and described.
